UNITED STATES PATENT OFFICE.

GEORGE D. ROEDELS, OF PALISADE, NEW JERSEY.

ATTACHMENT FOR VACUUM OR SUCTION CLEANING APPARATUS.

1,145,083.

Specification of Letters Patent.

Patented July 6, 1915.

Application filed March 15, 1911. Serial No. 614,561.

To all whom it may concern:

Be it known that I, GEORGE D. ROEDELS, a citizen of the United States, residing at Palisade, county of Bergen, State of New Jersey, have made a certain new and useful Invention in Attachments for Vacuum or Suction Cleaning Apparatus, of which the following is a specification.

The invention relates to attachments for use in connection with vacuum or suction cleaning apparatus for pneumatically cleaning or polishing floors, walls, ceilings, carpets, draperies, furniture or the like.

The object of the invention is to simplify and improve the construction of devices for pneumatically cleaning or polishing floors, ceilings, walls, carpets, draperies, furniture or the like, and to render the same more efficient.

20 A further object is to provide a device of the character referred to which is capable of being readily applied to the suction heads of different types and constructions of vacuum cleaning apparatus.

25 A further object is to provide an attachment of the character referred to which provides means to prevent furniture, floors, walls, ceilings or the like from becoming marred or injured by the attachment striking thereagainst when in use.

30 A further object is to provide a device of the nature and character referred to which is substantial, strong and durable, and not liable to get out of proper working order when in use.

Other objects of the invention will appear more fully hereinafter.

The invention consists substantially in the construction, combination, location, and relative arrangement of parts, all as will be more fully hereinafter set forth, as shown in the accompanying drawing, and finally pointed out in the appended claims.

In the drawing,—Figure 1 is a view in perspective, the handle being broken off, of a construction of attachment embodying the principles of my invention. Fig. 2 is a view in vertical transverse section on the line 2, 2, Fig. 1, looking in the direction of the arrows. Fig. 3 is a view in top plan, the handle or neck portion being in horizontal section, and parts broken out and in section, showing a slightly modified construction embodying my invention. Fig. 4 is a bottom plan view of the construction shown in Fig. 3. Fig. 5 is a view in vertical trans-

verse section on the line 5, 5, Fig. 3 looking in the direction of the arrows. Fig. 6 is a broken view in vertical longitudinal section on the line 6, 6, Fig. 3 looking in the direction of the arrows.

The same part is designated by the same reference sign wherever it occurs throughout the several views.

It is among the special purposes of my present invention to obviate defects existing in certain types of vacuum cleaners and in carrying out my invention I propose to provide the entrance slot into the hollow head, and through which the dust, dirt or the like is drawn by the suction action, at the bounding edges of the flat face of the head, and consequently at points in advance of the flat face of the head where the suction action may be exerted through the slot and upon the surface to be cleaned in advance of the movement of the flat face of the head over such surface. I also propose to provide the slot or opening at the bounding edge of the flat face of the head both front and rear, so that no matter in which direction the head is moved the suction action is exerted upon the dust, dirt or the like in advance of the movement of the head. I also propose to provide means whereby the suction draft into the head is exerted upon dust or dirt lying on the floor, for instance, in a direction which approaches parallelism with the plane of the floor at least in a region closely adjacent to the entrance into the head. I also propose to provide means for preventing the head, or the outer surfaces of the side edges thereof from scarring or marring furniture or other articles with which they may come in contact while the device is in use.

The features of my invention as above outlined may be embodied in a wide variety of specifically different structures and arrangements of details, without departure from the spirit and scope of my invention. While, therefore, I have shown and will now describe various operative and practical embodiments and forms of devices my invention, in its broadest scope as defined in the claims, is not to be limited or restricted to the specific construction and arrangement of details shown.

In the arrangement shown in Figs. 1 and 2, a head or member 10 is employed. This may be of the usual or any suitable shape or contour, and is made hollow, as indicated

2
 at 11, a socket or neck 12, communicating with the interior of the hollow head and affording means for attaching the usual tubular handle 13, by which the head is carried or manipulated in the operation of the device, or for attaching the hose or other connection to the vacuum or suction producing mechanism in the ordinary manner. Suitably supported within the chamber of the hollow head is a plate 14, lying in a plane substantially parallel with the plane of the lower edge of the head and presenting a flat face to rest upon the surface to be cleaned. This plate may be faced on its under surface with felt, cloth, fabric or other material, as indicated at 15, according to the uses and purposes to which the device is to be put. The plate 14, may be supported within the chamber in any suitable or convenient manner, as, for instance, by means of struts or cross pieces 16 secured to or formed with the frame of the head. In accordance with my invention I so arrange and support the plate 14 within the chamber 25 of the head that the under face of the facing 15 thereof, in case a facing is applied thereto, and which face rests upon the surface to be cleaned, extends below the lower surface 17, of the bounding side edge of the 30 head frame, as clearly shown in Fig. 2. I also support the plate 14 in off-set relation with respect to the inner side walls of the head, thereby providing the longitudinal slots or spaces 18, between the peripheral edges of the plate and its facing and the inner surface of the side walls of the head frame. I also propose to apply a strip 19 of flexible material such as cloth, fabric, rubber or the like, to the exterior surface of 40 the sides of the head frame and I arrange the lower edge of the strip 19 to extend somewhat below the surface 17, of the sides of the head frame, as indicated at 20.

It may sometimes be desirable to apply a 45 device embodying my invention as a separate detachable attachment to the heads of suction apparatus at present in use, whereby the attachment may be made and sold as a separate article of manufacture instead of 50 being incorporated into the structure of the head itself. In Figs. 3, 4, 5 and 6, I have shown such an embodiment of my invention, the head proper comprising the body 21, having the neck 22, for the hollow handle, 55 hose or other connection 23, said body being hollow as at 24. In this case, however, the under face of the closed hollow head is provided with the usual central elongated opening 25. The attachment comprises an open 60 hollow frame or member 26, which may be of any suitable contour or shape having secured thereto or formed therewith the cross pieces 27, to form supports for the plate 28, to which the facing 29 is applied, the plate 65 28 and its facing 29 being off-set from the

inner surface of the side pieces of frame 26 to form the channels or spaces 30. The lower face of the facing 29, extends slightly below the lower edge surface 31, of the frame side pieces 26, as clearly shown, so 70 that when the under face of the plate or its facing rests flat upon a surface to be cleaned the lower edges of the frame 26, are raised slightly above said surface. A strip 32 of suitable material such as cloth, fabric, rubber, or other flexible or resilient material is applied to the outer surface of the sides of frame 26, and so arranged that the lower edge thereof extends slightly below the lower edge of the side pieces of frame 26, but not 80 to the plane of the flat face of the plate 28 or its facing 29, as clearly shown.

The opposed surfaces of the edges of the plate 28 and its facing and the inner surface of the frame 26, are correspondingly bevelled as shown.

The attachment comprising the hollow frame 26, and the parts attached thereto, may be readily and easily applied to the head 21, in any suitable or convenient manner. I have shown a simple arrangement wherein the cross pieces 27, which support plate 28, have secured thereto suitable spring clips 33, adapted to snap into or through the slot 25, in the head 21. If desired a suitable packing strip 37, may be placed between the frame 26 and the lower face of head 21.

By reason of the fact that the lower face of the facing 15, 29, extends below the lower surface 17, 31, of the edge of the frame 10, 26, the suction action of the apparatus is applied to the dust or dirt on the surface to be cleaned in substantially the plane of, or a plane parallel with, the said surface. The extension of the lower edge of the flexible strip 19, 32, below the surface 17, 31, of the sides of frame 10, 26, secures this action. The upwardly and inwardly inclined opposed surfaces of the frame and the peripheral edges of plate and its facing facilitates the passage of particles of dust, dirt and the like into the interior of the head under the influence of suction action. The provision of the spaces or openings 18, 30, 11 all the way around the peripheral edges of the plate 14, 28, and the facing 15, 29, thereof enables the dust, dirt or the like to be drawn into the head from in front of the head as it advances over the surface to be cleaned, thereby insuring a most efficient 1 cleaning action of the suction apparatus.

Having now set forth the object and nature of my invention, and constructions embodying the principles thereof, what I claim as new and useful, and of my own invention, and desire to secure by Letters Patent is,—

1. In a vacuum cleaning apparatus, a hollow member having the chamber thereof adapted to be placed in communication with

- a vacuum producing means, and a plate supported within the chamber of said hollow member but off-set at its peripheral edges inwardly from the inner surface of the side walls of said hollow member to form spaces or openings therebetween, the outer face of said plate being flat and forming a supporting surface for the hollow member, said outer flat face having a covering extending beyond the plane of the lower edge of the hollow member. 2. In a vacuum cleaning apparatus, a hollow member having the interior chamber thereof adapted to be placed in communication with a vacuum producing means, and a plate supported within the chamber of said hollow member but offset at its peripheral edges inwardly from the inner surface of the side walls of said hollow member to form spaces or openings therebetween, a flexible strip applied to the exterior surface of the side walls of said hollow member, and having its lower edge extending below the plane of the lower edge of said side walls, the outer face of said plate being flat and having a covering forming a supporting surface for said hollow member, and extending beyond the plane of the lower edge of said flexible strip. 3. In a vacuum cleaning apparatus, a hollow member having a hollow frame forming an extension, the interior chamber thereof adapted to be placed in communication with a vacuum producing means, transversely extending members arranged within said chamber, a plate detachably connected to said transversely extending members, the outer face of said plate having a covering extending beyond the edges of the side walls of said hollow frame, the edges of said plate being spaced from the sides of the hollow frame. 4. In a vacuum cleaning apparatus, a hollow member having a frame forming an extension, the interior chamber thereof adapted to be placed in communication with a vacuum producing means, transversely extending supporting members arranged within said chamber and a plate detachably connected to said transversely extending members, the outer face of said plate forming a supporting surface for the hollow member and its extension, the peripheral edges of said plate being off-set, inwardly from the opposed surfaces of the walls of said hollow member extension to form slots or openings therebetween, the outer face of said plate having a covering extending beyond the lower edges of the side walls of the hollow member extension, and a flexible strip applied to the exterior surface of the side walls of the hollow member extension and having its outer edge extending beyond the lower edge of said side wall. 5. In a vacuum cleaning apparatus, a hollow member adapted to be connected to a vacuum producing means, a supporting member having a lower face to rest upon the surface to be cleaned, an inclosing frame for said supporting member, said frame offset from said supporting member at the peripheral edges of the latter, to form slots or openings between said peripheral edges and frame, said slots or openings delivering into the interior of the hollow member. 6. In a vacuum cleaning apparatus, a hollow member adapted to be connected to a vacuum producing means, a supporting member having a lower face to rest upon the surface to be cleaned, and an inclosing frame for said supporting member, said frame being off-set from said supporting member to form slots or openings at the peripheral edges of said supporting member, said slots or openings delivering into the interior of the hollow member, the plane of said supporting face lying parallel with and extending beyond the plane of the lower surface of the outer bounding walls of said slot or opening. 7. In a vacuum cleaning apparatus, a head having a chamber to be connected to a vacuum producing means, and a central slot in the lower face thereof, in combination with an attachment adapted to be removably applied to said face, said attachment having a face to rest upon the surface to be cleaned and a surrounding frame off-set from said face to provide slots or openings at the peripheral edges of said face, said slots or openings being in communication with the central slot in the face of said head. 8. In a vacuum cleaning apparatus, a hollow head adapted to be connected with a vacuum producing means and having a central slot in the lower face thereof, in combination with an attachment having retaining devices for detachable connection of said attachment to the head, said attachment having a supporting face to rest upon the surface to be cleaned, and a surrounding frame therefor, said frame being off-set from the face to provide elongated slots at the peripheral edges of said supporting face, said slots being in communication with the central slot in the head face. 9. In a vacuum cleaning apparatus, a hollow head adapted to be connected with a vacuum producing means and having a central slot in the lower face thereof, in combination with an attachment having retaining devices for detachable connection with said head, said attachment having a supporting face, to rest upon the surface to be cleaned, and a surrounding frame therefor, said frame being off-set from the face to provide elongated slots or openings at the peripheral edges of said supporting face, the plane of said supporting face lying par-

allel with but extended beyond the plane
of the lower edges of the outer bounding
walls of said slots, said last mentioned slots
being in communication with the central
slot in the lower face of the head.

In testimony whereof I have hereunto set
my hand in the presence of the subscribing

witnesses, on this 11th day of March, A. D.,
1911.
